CLAIM

The ornamental design for a combined fifth wheel pin
puller and tire knocker for tractor trailer hitch assem-
blies, as shown and described.

DESCRIPTION

FIG. 1 is a side elevational view of the combined fifth
wheel pin puller and tire knocker for tractor trailer
hitch assemblies showing my new design;

FIG. 2 is a top plan view thereof;

FIG. 3 is a bottom plan view thereof;

FIG. 4 is a perspective view thereof.

FIG. 3
